UNITED STATES PATENT OFFICE.

HENRY M. KEITH, OF WEST FRANKFORT, ILLINOIS.

BRUSHING MACHINE.

Application filed July 28, 1922. Serial No. 573,213.

The object of this invention is to provide a machine for brushing clothes and polishing shoes, the clothes brushing mechanism including a positively driven element mounted in a suction nozzle.

A further object is to provide a machine in which the suction nozzle is connected with a section of flexible tubing, the latter being wound on a reel, and means being provided for returning the reel to normal position after the user has finished the cleaning operation.

A further object is to provide a hose, having a suction nozzle, means for producing suction, a brush mounted within the nozzle, and a flexible shaft connection permitting rotary movement to be transmitted to the brush through the reel and hose.

A still further object is to provide for producing suction through the axial element of the reel and to provide the necessary drive for the flexible shaft by a belt passing over two pulleys, one of which has its axis concentric with the axis of the reel, and the other of which is mounted on the reel, near the periphery thereof.

A still further object is to provide a shoe polishing device driven by a motor which imparts motion to a fan for producing suction, and also imparts motion to the flexible shaft.

With the foregoing and other objects in view, the invention consists in the novel construction and arrangement of elements described and claimed, it being understood that modifications may be made within the scope of the claims without departing from the spirit of the invention.

In the drawings,

Figure 1 is a view of the machine in front elevation; Figure 2 is a side elevation; Figure 3 is a vertical section through the casing, showing the inclosed mechanism chiefly in elevation; Figure 4 is a section on line 4-4 of Figure 3; Figure 5 is a vertical section on line 5-5 through the lower part of the housing, showing the shoe brush and motor; Figure 6 is a section through the housing of the clothes brush; Figure 7 is a section on line 7-7 of Figure 5; Figure 8 is a section on line 8-8 of Figure 3; Figure 9 is a section on line 9-9 of Figure 3; Figure 10 is a detail view showing means for engaging the upper end of clutch controlling lever 47; Figure 11 shows diagrammatically the electrical connections of the motor; Figure 12 is

a detail showing the drive from belt 39 of Figure 3 to the flexible shaft 34 of clothes brush 33.

Within the base 10, I mount a motor 11 including an armature shaft 12, this shaft carrying a fan 13 within the fan casing 14.

An air duct 15 extends vertically of the upright portion 16 of the housing, and the upper air connection 18 is deflected horizontally as shown, and is in alinement with the hollow axial element 19 of the reel 20. The elements 18 and 19 abut each other, but member 19 is rotatable, and a continuous passage is provided through radial tube 21 of the reel, through axial element 19 which is in fact a part of the radial portion 21, and through the elements 18 and 15, the latter having communication with the fan casing. A bearing is shown at 23.

A section of rubber hose 26 is secured to the reel by means of a connection 25, air communication being established through this connection between the element 21 and the hose.

Carried by the end of the hose is a nozzle member 30 of about the form shown and having an opening at one side thereof.

Within the nozzle 30 is a rotary brush 33, driven by a flexible shaft 34 (passing through the hose) by means of gearing 35 and short shaft 37 carrying a pulley 38. This pulley is driven by a belt 39 passing around a pulley 40 on a shaft 41, the latter carrying a pulley 42 driven by a belt 43 operated from pulley 44 on motor shaft 12.

The pulley 44 is normally loose but carries a clutch element 45 engaged by the splined clutch member 46 controlled by lever 47 pivoted at 48. When the air hose is drawn out, a pin 49 on the reel engages the upper end of the lever and moves the lower end to the left, for shifting the clutch element 46 and causing it to engage the clutch element, on pulley 44, so that the latter will drive the belt 43. Lever 47, if made slightly resilient, will be cleared by pin 49 as the upper end of the lever moves to the right.

A cylindrical shoe brush 50 is mounted on the shaft 51 carrying a pulley 52 driven by a belt 53 and pulley 54 on the shaft 12. Pulley 54 carries a clutch element 55 engaged by the slidable clutch member 46, when lever 47 is thrown in the opposite direction due to the automatic rewinding of the reel by a spring 57. In this rewinding operation, pin 49 of Figure 3 moves to the left and the lower

end of lever 47 moves to the right, returning clutch element 55 to the position of Figure 3. The normal position of the clutch is such that the shoe brush starts when the 5 motor is started and operates until the hose is drawn out or the electric switch is thrown out.

The motor shaft 12 carries a device or devices 60 operated by centrifugal action, so 10 that when the motor shaft is rotating at sufficient speed, the cover 61 (normally closing the opening 62 in the housing, providing access to the shoe brush) is open. The mechanism (including arm 60' of Fig. 5) for effecting this result, is shown conventionally but not claimed in this case. A rubber garment protecting device is shown at 63.

The fan or blower 13 removes dust from the shoe brush through the duct 65, and a 20 three way connection 66 (Fig. 8) is interposed between the fan housing (Fig. 3) and the air passages leading from the shoe brush and clothes brush for carrying dust therefrom to bag 68.

25 The feed wires 70, 71 of the motor are controlled by switch arm 72, placed in a convenient position, so that it may be controlled, if desired, by coin mechanism, not shown.

It is intended that the casing or housing 30 for the entire machine shall be of ornamental appearance, and the mirror 75 is carried by the upper portion of the casing and a second mirror 76 is mounted on the column, or central portion of the casing. It should be 35 added that the brush 33 is preferably of spiral form, and the manner of mounting permits of the use thereof on all portions of a person's clothing, and also on the hat.

40 A time controlling device may be placed in such convenient position that the deposit

of the coin will automatically break the circuit and stop the motor upon the expiration of a specified interval, say—three minutes. The coin operated and electrically controlled mechanism is described and claimed in a 45 separate application.

What is claimed is:

1. In a machine of the class described, a reel, a flexible tube to be wound on the reel, a cleaning device including a nozzle and rotary brush, the nozzle being connected with the tube, means for producing suction through the reel tube, and nozzle, driving means for the rotary brush, a clutch connected with an element of the driving means, means for automatically rewinding the flexible tube when unwound, a clutch operating lever, and a device carried by the reel and engaging the end portion of the lever for shifting the clutch and controlling the driving means. 50

2. In a machine of the class described, a reel, a hose wound on the reel, means for producing suction through an element of the reel and the hose, a suction nozzle connected with the hose, a flexible shaft and a rotary brush connected therewith and means mounted on the reel for driving the flexible shaft. 55

3. In a machine of the class described a reel, a hose wound on the reel, means for producing suction through an element of the reel and the hose, a suction nozzle connected with the hose, a flexible shaft and a rotary brush connected therewith, a driven element 70 rotatable about an axis coincident with the axis of rotation of the reel, and means for imparting motion from said driven element to the flexible shaft. 75

In testimony whereof I affix my signature.
HENRY M. KEITH.
